(57) **CLAIM**

The ornamental design for an electronic lock housing, as shown and described.

DESCRIPTION

FIG. 1 is a perspective elevation view of the electronic lock housing;

FIG. 2 is another perspective elevation view of the electronic lock housing of FIG. 1;

FIG. 3 is a front view of the electronic lock housing of FIG. 1;

FIG. 4 is a top view of the electronic lock housing of FIG. 1;

FIG. 5 is a right side view of the electronic lock housing of FIG. 1; and,

FIG. 6 is a perspective view of the electronic lock housing of FIG. 1, shown in its environmental use, the housing being mounted on furniture. The broken lines showing of furniture is for illustrative purpose only and forms no part of the claimed design.

1 Claim, 4 Drawing Sheets
